UNITED STATES PATENT OFFICE

ROLPH J. LACKNER, OF OZONE PARK, NEW YORK

HOOKED CLAMP

Application filed September 28, 1929. Serial No. 395,921.

This invention relates to swinging scaffolds and has for its object the provision of means whereby the safety of the workmen will be promoted. The invention provides 5 novel constructions whereby the guard cable may be adjusted to the length of the scaffold and also whereby a movable device will be provided to grip a cable so that the anchoring devices will be firmly secured and in the 10 event of an accident the workmen will be so supported that they may be easily rescued without injury. The invention is illustrated in the accompanying drawings and will be hereinafter first fully described and then 15 more particularly defined in the appended claim.

In the drawings:

Figure 1 is a perspective view of a swinging scaffold in its position of use and 20 equipped with my improved safety devices,

Fig. 2 is an elevation of the anchoring elements,

Fig. 3 is an enlarged detail perspective view of a corner brace and guide which is 25 employed in connection with the anchoring cable,

Fig. 4 is an enlarged perspective view of a cable clamp,

Fig. 5 is a plan view of a snap hook and 30 cable guide,

Fig. 6 is a similar view with the upper clamp plate removed,

Fig. 7 is a detail section on the line 7—7 of Fig. 5, and

Fig. 8 is a longitudinal section on the line 8—8 of Fig. 5.

Referring particularly to the drawings, the numeral 1 indicates the anchoring roof irons which are of the usual form and rest 40 upon wear plates or boards 2 disposed upon the cornice of a building and projecting beyond the same so that the scaffold-supporting cables will be held out of contact with the front of the building. The inner ends of 45 these roof irons are each formed into an eye 3 in which is engaged a snap hook 4 on the end of the anchoring cable 5. The cable 5 is passed around a chimney 6 or other fixed part of the building, such as a skylight, and 50 the inner end thereof is connected with the

main length of the cable by a clamp device 7 which is shown more in detail in Fig. 4. At each corner of the chimney 6, 1 provide a wear and guide bracket 8, the body of which has a right angular seat or notch 9 in one side whereby it is adapted to fit against the corner of the chimney, skylight or other fixed element and upon the outer side it is formed with horizontal ribs 10 defining grooves in which the cable may rest, and at the apexes 60 of the upper ribs is inserted a vertically disposed retaining bolt 11 which is adapted to bridge the portion of the cable seated between said ribs and thereby retain the cable in place. It will be understood that when 65 several turns of the cable are made around the chimney at least one turn will be disposed in the upper groove, and the bolt 10 serves to retain said run so that it will not interfere with any of the other runs and will not slip away from the guide bracket. These brackets support the cable out of contact with the chimney and thereby avoid wear upon the cable and also upon the chimney. The anchoring cable clamp 7 consists of a head member 12 having an overhanging flange 13 along its upper edge on one face, said flange having depending lugs or keepers 14 at its ends whereby the head is adapted to extend over the cable and rest thereon. Pivoted upon the 80 depending portion of the head below the overhanging flange is a trigger or lever 15 which depends below the head and has an opening 16 through its lower extremity in which the end of the cable may be secured, 85 preferably by the provision of a snap hook, indicated at 17. As shown in Figs. 2 and 4, the upper end of the trigger 15 is disposed immediately below the cable and its upper edge is formed on a concave arc, as indicated at 18, whereby the ends or corners 19 will acquire the functions of cams to bind the cable against the under side of the overhanging flange 13 whenever the trigger is swung 90 to one side, as will be understood upon reference to Fig. 2. As long as the trigger is perpendicular or at a right angle to the flange, the cable may slide freely between the flange and the end of the trigger and the clamp 95 may, consequently, be shifted along the cable 100

to such point as may be desired or at which it will be most efficient. Should anything happen which would put a strain upon the portion of the cable attached to the trigger, 5 the resulting pull will rock the trigger about its pivot 20 so that one or the other corner 19 will be caused to bind the length of the cable passing along the flange so that it will be firmly clamped between the trigger and the 10 flange and, consequently, will be firmly secured. It will be understood that in hanging the scaffold the anchor cable will be drawn taut so that the trigger will be maintained 15 constantly in the clamping position shown in Fig. 2 and, consequently, the cable will firmly retain the roof irons in their set positions.

Suspended from the front ends of the roof irons in any approved or the usual manner 20 are pulley blocks 21 through which are trained the suspending cables 22. The lower portions of these cables are trained through pulley blocks 23 in the usual manner and said pulley blocks are equipped with hooks 24 engaged in the usual eyes at the upper ends of the scaffold irons 25, the scaffold platform 26 being passed through and supported by these irons in a well known manner. The irons 25 are formed with the 25 guard arms 25' which rise from the irons and are provided with loops 27 at their upper ends, a guard cable 28 being passed through these loops and connected with the lower pulley blocks 23 in the manner fully 30 disclosed in Letters Patent, No. 1,568,285, issued January 5, 1926. In the present instance, the guard cable 28 is provided with snap hooks 29 to be engaged in the eyes on the under sides of the pulley blocks 23, these 35 snap hooks providing a more secure hold and being more easily manipulated than merely tying the cable into the eyes or rings. The snap hooks 29 are shown in detail in Figs. 5 to 8 and comprise a hook member 40 bridged by a spring-pressed lever 30 in the usual manner. The shank or body of the hook comprises a lower plate 31 integral with the hook and having longitudinal 45 grooves 32 formed in its upper surface adjacent its side edges. These grooves are preferably V-shaped, as shown in Fig. 7, and at their inner ends they merge into a recess 33 formed in the upper surface of the plate adjacent the base of the hook element, the outer 50 ends of the grooves opening through the end edge of the plate. There is also an upper clamping plate 34 which is formed with longitudinal grooves 35 in its under surface to mate with the grooves 32 in the lower plate 55 and the grooves 35, like the grooves 32, merge into a circular recess 36 in the under side of the upper clamping plate. A grooved roller 37 is mounted in the registering recesses 33 and 36 and is fitted upon a bolt 38 equipped 60 with a nut 39 whereby when the nut is

turned home the roller will be maintained within the mating recesses and the plates will be secured together. A second bolt 40 is inserted through openings provided therefor adjacent the outer ends of the plates and this bolt is equipped with a wing nut 41 to be turned home against the upper clamping plate so that the two plates may be very firmly secured together. The guard cable 70 28 has its end portions seated in the grooves 32, 35 so that when the securing nuts are turned home the cable will be very securely clamped and slipping of the same cannot occur. By merely loosening the securing nuts, 75 the cable may be shifted through the clamp and thereby adjusted so that it will be accommodated to the length of the scaffold and a single cable may thus be used at times upon many different scaffolds.

It will be noted that the base of the hook 80 is expanded laterally to the width of the clamping plate and merges into the end of the plate so that the strain will be applied along the medial line of the device. All parts of the pulley and the bight of the cable 85 are completely housed by the clamping plates so that these parts will not be exposed in any portion and, consequently, cannot be displaced or bent or otherwise damaged by 90 blows from falling objects.

The workmen are fitted with belts 42 to 95 which is firmly attached a short cable 43 sufficiently long to permit the workmen to move freely as their labors demand and at the outer ends of these cables are snap hooks 44 engaged in triggers 45 the same in all respects as the trigger 15 shown in Figs. 2 and 4 and previously fully described. The triggers 45 are mounted upon and cooperate with heads 46 which are of the same construction as 100 the heads 12 and operate in the same manner. The heads 46 are engaged over the cable 28 so that as long as the trigger hangs perpendicularly the heads may move freely along the cables in the manner of a trolley. Should 105 the suspending cables 22 break so that the scaffold would be tilted or drop at one end, the cables 43 would be immediately subjected to a pull which would cause the cable 28 to be clamped by the triggers 45 and heads 46 and 110 the workmen would, consequently, be suspended on the guard cable and held thereby until they could be rescued.

The scaffold would not be entirely freed in 115 the event of a breakage in the suspending cables inasmuch as it is equipped at its ends with the safety clamping devices 46 which are fully shown and described in Letters Patent, No. 1,488,822, issued April 1, 1924.

Having thus described the invention, I 120 claim:

A device for the purposes set forth comprising clamp plates provided in their opposed faces with longitudinal mating grooves and with recesses at the inner ends of the 125 130

- grooves, said grooves being V-shaped in cross section and the recesses being of less diameter than the width of the plates, a pulley mounted in the mating recesses and about which the
5 bight of a cable is trained with the sides of the bight engaged in the grooves, a hook having its base expanded laterally to the width of the clamping plates and merging into the recessed end of one of said plates for engaging
10 a scaffold-suspending device, a bolt inserted through the recessed ends of the plates to secure them together and constitute an axle for the pulley, and a bolt inserted through the opposite ends of the plates between the
15 grooves whereby the plates and the bight of the cable will be firmly clamped together.

In testimony whereof I affix my signature.
